E. B. STELTER

FORCE PUMP OIL CAN

Filed March 11, 1922

Fig. 1.

72 Inventor
Edward B. Stetter;
334 Attorney
Watson E. Coleman

UNITED STATES PATENT OFFICE.

EDWARD B. STELTER, OF HINGHAM, MONTANA.

FORCE-PUMP OIL CAN.

Application filed March 11, 1922. Serial No. 542,922.

To all whom it may concern:

Be it known that I, EDWARD B. STELTER, a citizen of the United States, residing at Hingham, in the county of Hill and State of Montana, have invented certain new and useful Improvements in Force-Pump Oil Cans, of which the following is a specification, reference being had to the accompanying drawings.

10 This invention relates to dispensing cans for containing lubricating oil, and particularly to cans of that type wherein means are provided for positively forcing the oil out of the can.

15 The general object of this invention is to provide an oil can of this type having a plunger and means whereby the plunger may be given a step by step movement to force the oil out of the outlet nozzle.

20 A further object is to provide means actuated by the finger or thumb of the hand for giving said step by step movement.

A still further object is to provide a device of this character which is not complicated with check valves for preventing the reverse flow of the oil which valves are very liable to get out of order, and further to so construct the can that it makes no difference in what position the can is held in 25 discharging the oil.

Another object is to provide a can of this character which may be taken apart readily for cleaning or adjustment whenever desired.

35 Other objects will appear in the course of the following description.

My invention is illustrated in the accompanying drawings, wherein:—

Figure 1 is a vertical sectional view 40 through my improved dispensing can, the section being taken on the line 1—1 of Figure 2;

Figure 2 is a top plan view of the construction shown in Figure 1;

45 Figure 3 is a sectional view of the tubular piston rod 19 above the holder 29;

Figure 4 is a like view above the holder 34;

50 Figure 5 is an enlarged sectional view of the spout 19 and the holding devices therefor.

Referring to these drawings, 10 designates the body of the oil can, which is provided preferably with the upwardly bowed top 11 which is preferably, though not necessarily, pressed or cast integral with the

body 10. The lower end of the oil can is outwardly flared, as at 12, and exteriorly screw-threaded for engagement with the flanges of a bottom 13. The top 11 is formed with a filling opening normally closed by a cap 14 and with an outlet opening defined by an exteriorly screw-threaded flange 15 adapted to engage a union 16 whereby the flanged end of the spout 17 is held in place. This spout has any desired or usual form.

The top 11 has a gland or packing nut 18, through which passes a piston rod 19. This piston rod is tubular and is open at its lower end and at its upper end is formed with a gooseneck 21 which is so disposed that when the piston rod is lowered, the opening at the lower end of the gooseneck is immediately over the filling opening of the can. Carried upon the lower end of the piston rod and held in place by the nuts 22 is a piston 23 formed of upper and lower disks with an interior core of heavy cloth 24 which is riveted to the disks and extends out beyond these disks to engage with the wall of the body 10 to prevent passage of oil around the piston.

For the purpose of giving a step by step movement to the piston, I mount upon the bifurcated bracket 25 attached to the top 11 the lever 26 constituting a finger piece and having its relatively flat and wide outer end disposed above the handle 27 of the can so that the thumb may be used to depress the outer end of this lever. The inner end of this lever is connected by a pair of pivoted links to a lifting and locking dog 29 having a slot 30 whose axis extends diagonally through the lever and whose width is equal to the diameter of the rod 19, the length of this slot being somewhat greater than the rod 19 so that the locking dog may oscillate. When this locking dog 29 is in a horizontal position or at right angles to the rod 19, the end walls of the slot 30 are nearly parallel with the rod 19, and the dog does not bind upon the rod 19, but when this dog is raised or canted by an upward movement of the link 28 due to a depression of the lever 26, 105 the locking dog will tend to shift into a more or less acute angle to the rod 19 and bite against this rod and then as the dog 29 is raised, the piston rod or plunger will be raised. When this locking dog is in a horizontal position there will be no binding action and the piston rod will pass freely

through the opening 30. That end of the dog 29 opposite the links 18 is connected to a coiled contractile spring 31 attached at its lower end to the top 11 in any suitable manner, as to a bracket 32. This bracket 32 carries a pair of rings 33 which extend upward and to the upper end of which is pivoted a locking dog 34 which also has a slot 35, this slot having a width slightly greater than the 10 diameter of the piston rod 19 and a length greater than the diameter of the rod and having its axis disposed at an inclination to the face of the dog 34 and at an angle opposite to the angle of the slot 30. Thus 15 when this locking dog 34 approximates a horizontal position it will bind upon the rod or plunger 19 and lock the rod 19 against tilting. When it is slightly raised, however, by an upward movement of the plunger or 20 rod, the edges of the slot 35 will release their grip upon the rod and the rod may pass upward freely therethrough. The free end of this locking dog 34 is drawn downward by a coiled contractile spring 36 which is 25 connected to the lever 26, this spring acting to depress the locking dog 34 in its rod clamping position.

It will be understood that in the operation of this device the oil is disposed above the 30 piston 23 and that the oil is ejected from the spout 17 by causing the piston to move toward the spout. Some leakage of oil will occur, however, between the piston 23 and the wall of the body 10 and by providing the 35 elbow or gooseneck 21 it is possible, by forcing the piston down, to cause this oil which has leaked past the piston to pass up through the air vent formed by the pipe 19 and out through this elbow 21 and back into the oil 40 can through the opening normally closed by the cap 14. Ordinarily, however, there will be no oil below the piston.

To operate the device, the spring end or free end of the holding dog or device 34 is 45 lifted up until it is inclined to the horizontal and the plunger is forced all the way down as far as it will go. The cap 14 is then unscrewed and oil is filled into the can and the cap replaced. If it then be desired to discharge the oil the body is held by the handle 27 and the thumb is placed on the lever 26. Then by pressing down on the lever 26 it lifts the dog or locking device 29 about one-eighth of an inch. This lifts the plunger up 55 about one-eighth of an inch, causing a discharge of a certain amount of oil. Lifting the plunger raises the locking dog 34 from its position shown in Figure 5 and permits the upward movement of the plunger. The 60 function of the dog 34 is to keep the plunger rod from moving downward when the dog 29 is moving downward and getting a new hold. When the pressure on the lever 26 is released, the dog 34 immediately engages the 65 rod 19 to prevent its further descent while

the dog 29 moves downward. Again pressing upon the lever 26 will lift the plunger 19 another stroke of one-eighth of an inch, and so by consecutive depressions of the lever 26, a step by step movement of the plunger rod 19 will be given, carrying the piston toward the spout 17 and discharging the oil little by little.

It will be obvious that the can can be 75 readily taken apart by unscrewing the bottom 13 and removing the elbow or gooseneck 21 from the upper end of the plunger. Then the plunger can be pushed out of the body 10 and the plunger and plunger rod entirely removed. The lower end of the body is 80 flared, as at 12, simply to permit the ready insertion of the plunger. It will be seen that however the can be inverted no oil will 85 flow from the can and that it can only be forced out of the can by positive actuation of the plunger through the action of the thumb lever 26.

While I have illustrated a construction 90 which is particularly effective for the purpose intended, which is very simple, compact and does not readily get out of order, I do not wish to be limited to this, as it is 95 obvious that many changes might be made in the details of construction and arrangement of parts without departing from the spirit of the invention as defined in the appended claims.

I claim:

1. A dispensing oil can having a discharge 100 spout, a plunger disposed within the can, a plunger rod attached to the plunger and extending through that end of the can having the discharge spout, finger actuated means for giving a step by step motion to the plunger toward the spout, and means for holding the plunger from reverse movement, said means being rendered inoperative by movement of the plunger toward the spout.

2. A dispensing oil can having a spout, a plunger operating through the can and having a tubular plunger rod, a thumb actuated lever, a locking dog operatively and pivotally connected to the lever and having an aperture through which the plunger rod passes, means normally holding the locking dog in a position at right angles to the plunger rod, a depression of the lever acting to cant the dog to cause it to bind upon the plunger rod, a second locking dog yieldingly held in a position to bind upon the plunger rod and prevent backward movement of the plunger rod, the second named dog permitting the upward movement of the plunger rod.

3. In an oil can, a body having a spout at one end, a cap closing the opposite end of the body, a plunger disposed within the body and movable toward or from the spout, a tubular plunger rod extending out through that end of the body upon which the spout

is disposed, this end of the body having a filling opening and the rod having an elbow disposed with its discharge end in alignment with the filling opening whereby oil which 5 may have leaked into the space between the plunger and the cap may be forced out through the tubular plunger rod and back into the can above the plunger.

4. An oil can of the character described 10 comprising a body open at one end, a cap detachably engaged with the open end of the body, a plunger disposed in the body, a plunger rod extending through the end of the body opposite the cap, manually oper- 15 able means at this end of the body whereby a step by step motion may be given to the

plunger rod in a direction to carry the plunger away from said cap, and means normally preventing the retractive movement of said plunger and plunger rod, both 20 of said means being shiftable to a position to permit the plunger rod to be withdrawn from engagement therewith and the plunger withdrawn from the can upon the removal of said cap, said means permitting the plunger rod to be withdrawn and the plunger withdrawn from the can upon the removal of said cap. 25

In testimony whereof I hereunto affix my signature.

EDWARD B. STELTER.
